J. M. CONLEY,
REVOLVING SELF DUMPING LEVELER,
APPLICATION FILED JAN. 10, 1920.

1,373,799.

Patented Apr. 5, 1921.

INVENTOR.
John M. Conley
BY *Benj. Webster*
ATTORNEY

UNITED STATES PATENT OFFICE.

JOHN M. CONLEY, OF STOCKTON, CALIFORNIA.

REVOLVING SELF-DUMPING LEVELER.

1,373,799.

Specification of Letters Patent. Patented Apr. 5, 1921.

Application filed January 10, 1920. Serial No. 350,563.

To all whom it may concern:

Be it known that I, JOHN M. CONLEY, a citizen of the United States, residing at Stockton, in the county of San Joaquin, 5 State of California, have invented certain new and useful Improvements in Revolving Self-Dumping Levelers; and I do declare the following to be a full, clear, and exact description of the same, reference being had 10 to the accompanying drawings, and to the characters of reference marked thereon, which form a part of this application.

This invention relates to improvements in land levelers or scrapers, and particularly to 15 a type preferably drawn by a tractor.

The principal object of the invention is to provide a device of this character which will be controlled by the driver of the tractor, from his seat thereon, and in which the 20 scraping element may be dumped, set for loading lifted clear of the ground or flush therewith, and automatically held in any one of such positions as may be desired, merely by the manipulation of a pair of 25 cables or ropes on the part of the operator, without any great physical effort on his part.

A further object of the invention is to provide a scraping member with a double 30 or opposed scraping edge, so that not only will the weight of the metal parts be counterbalanced, but the scraping member will give twice the service of a single blade member.

35 A further object of the invention is to produce a simple and inexpensive device, and yet one which will be exceedingly effective for the purposes for which it is designed.

40 These objects I accomplish by means of such structure and relative arrangement of parts as will fully appear by a perusal of the following specification and claims.

In the drawings similar characters of reference indicate corresponding parts in the several views.

Figure 1 is a perspective elevation of the leveler.

Fig. 2 is an enlarged fragmentary side 50 view of a positioning-lock means.

Fig. 3 is a cross section taken on a line 3-3 of Fig. 2, showing the adjustable bearing box.

Referring now more particularly to the 55 characters of reference on the drawings, the numeral 1 denotes the side frames of the

scraper, preferably a rigid built-up iron structure, and provided with bottom runners 2. Cross beams 3 are provided at the upper ends to maintain the frames in spaced relations.

Fixed vertically to the frames on the outside and substantially central thereof are slotted bearings 4 in which boxes 5 are mounted for vertical adjustment, such adjustment being effected by set screws 6 bearing against the boxes.

Turnable in the boxes and projecting therethrough is a shaft 7 to which is fixed between the frames 1 a plurality of double-armed spiders 8, having opposed flat faces to which scraper plates 9 are secured, which extend from side to side between the frames. That is, one such plate is positioned to one side of said shaft while the other projects 75 from the other side, so that both plates are in parallel planes.

One of these plates at a time is adapted to project a short distance below the ground when angled forwardly, the lower edge of 80 such plate being curved forwardly somewhat as at 9^a, so as to form a kind of scoop.

Adjacent the shaft 7, the plates bend away therefrom substantially at right angles thereto, to form overhanging lips or 85 deflector plates 10.

Extending across the front end of the frames, being secured to the cross beam 3, is another plate 11 which projects horizontally toward the rear to a point where the 90 scraper plates will just clear the same when they turn about the shaft.

The purpose of these plates 10 and 11 is to prevent to a certain extent the dirt from working out over the edges when a full load 95 is being transported for dumping.

A rigid drawbar structure 12 is fixed to the forward end of the frames near the ground, being adapted for connection to the frame 13 of a tractor.

Fixed to the outer end of the shaft 7 on one side is a ratchet wheel 14, while turnably mounted on the shaft adjacent said wheel is a lever 15 having a pawl 16 adapted to engage the teeth of the wheel, the 105 teeth pointing to the rear at the point of engagement of the pawl therewith.

This lever is normally pulled back by a spring 17 secured thereto and to the frame 1, while a cable 18 extends forwardly to the 110 tractor to be within easy reach of the driver thereof.

Fixed to the other end of the shaft 7 is a notched wheel 19 having four spaced pairs of peripheral notches or recesses 20, two corresponding pairs being positioned relative to one of the plates 9, and the other two pairs similarly positioned relative to the other plate.

A bell crank 21 is pivotally mounted to the frame 1, the lower end of such member forming a pawl 21^a adapted to engage any one at a time of the notches 20, being normally kept in engagement therewith by a spring 22.

A cable 23 extends from the top of the member 21 to the driver of the tractor.

The notches 20 face in the opposite direction from the ratchet teeth of the member 14, so that when the cable 18 is pulled, the pawl 16 engages the teeth, whereas when the cable 23 is pulled, the pawl 21^a is disengaged from the teeth.

Inasmuch as the entire strain of the scraping is carried by the members 19 and 21, they must naturally be of very rigid and substantial construction.

In operation one of the scraper blades is normally positioned with its lower edge below the level of the runners, as stated. This position is maintained during the forward movement of the device, by the pawl 21^a engaging with notch "A."

If it is desired to transport the load some distance before dumping the same, the tractor is backed up slightly, which will cause the scraper blade to come to the level of the runners, turning somewhat on the shaft 7 to do this. The pawl 21^a then engages notch "B," and when the tractor again moves forward, the blade 9 will maintain the position thus had.

When it is desired to dump the load, the cable 23 is pulled, thus releasing the member 19 and the shaft 7 secured thereto, which will cause the lower edge of the scraper plate to bite into the ground and hold there while the framework of the scraper continues to move forward, the plate of course tilting about the shaft as an axis.

When in such dumped or upset position, the scraper may so be held indefinitely for transportation or otherwise, by reason of the pawl 21^a engaging either one of the two notches "C," these two being close together so that the plate may be held two or four inches or thereabouts above the ground, as may be desired.

To position the scraper for reloading, the cable 23 is first pulled to release the pawl

21, and the cable 18 then pulled, released and pulled again until the formerly idle scraper plate is in position adjacent the ground, when the cable 23 is slackened, and the plate held in such position by reason of the pawl 21 engaging the corresponding notch.

If desired, the lips 10 may be longer than shown, and project at a lesser angle to the plates 9, so that when the latter are reversely angled to a leveling or distributing position, and working with wet dirt, the load of dirt being distributed will be more or less broken up and retarded, so as to lessen the tendency of the wet mass to raise the plate 9 up and pass thereunder all at once.

From the foregoing description it will be readily seen that I have produced such a device as substantially fulfills the object of the invention as set forth herein.

While this specification sets forth in detail the present and preferred construction of the device still in practice such deviations from such detail may be resorted to as do not form a departure from the spirit of the invention, as defined by the appended claims.

Having thus described my invention what I claim as new and useful and desire to secure by Letters Patent is:-

1. A scraper comprising a frame adapted to be drawn by a tractor, a transverse shaft turnably mounted in the frame but normally held against turning, a pair of oppositely disposed scraper plates secured to the shaft, one at a time being adapted to rest adjacent the ground, means controllable at will for permitting the shaft to turn whereby the scraper will automatically upset with the forward movement of the tractor, and means for then turning the shaft in the same direction, to position the other scraper plate for loading.

2. A scraper comprising a frame adapted to be drawn by a tractor, a transverse shaft turnably mounted in the frame but normally held against turning, a pair of oppositely disposed scraper plates secured to the shaft, one at a time being adapted to rest adjacent the ground, a ratchet wheel fixed to the shaft, a lever loosely mounted thereon, a spring normally pulling the same to the rear, a pawl on the lever engaging the ratchets and arranged to rotate the wheel with a forward pull on the lever, and controllable means on the other end of the shaft for normally preventing the same from being turned.

In testimony whereof I affix my signature.
JOHN M. CONLEY.
